ABSTRACT

A jack device is disclosed herein for raising a tractor or the like. The jack device comprises a horizontally disposed frame means having a pair of supports pivotally connected at their upper ends to the opposite ends thereof. Spaced apart wheels are provided on the lower ends of the supports. A hydraulic cylinder means extends between the supports and is adapted to pivotally move the supports with respect to the frame means. Means is provided on the upper end of the frame means for engagement with the tractor to support the same thereon. The hydraulic cylinder is extended so that the frame means is lowered to permit the jack to be positioned beneath the tractor. The hydraulic cylinder is then operated to retract the cylinder rod therein which causes the supports to pivotally move towards each other whereby the frame means is raised upwardly into engagement with the tractor which causes the tractor to be raised from its supporting surface.

JACK DEVICE FOR TRACTORS AND THE LIKE

Therefore, it is a principal object of this invention to provide an improved jack device for tractors and the like.

A further object of this invention is to provide a jack device having means thereon for permitting the jack to accommodate various types of tractors.

A further object of this invention is to provide a jack device which is conveniently positioned beneath the tractor.

A further object of this invention is to provide a jack device which is operated by the tractor hydraulic system.

A further object of this invention is to provide a jack device which may be used to raise and support the rearward end of the tractor or the front end of the tractor.

A further object of this invention is to provide a jack device which is economical of manufacture, durable in use and refined in appearance.

These and other objects will be apparent to those skilled in the art.

This invention consists in the construction, arrangements and combination of the various parts of the device, whereby the objects contemplated are attained as hereinafter more fully set forth, specifically pointed out in the claims, and illustrated in the accompanying drawings, in which:

FIG. 1 is a rear perspective view of the device of this invention;

FIG. 2 is a side view of the device positioned below the rearward end of a tractor, the jack being in a lowered condition;

FIG. 3 is a view similar to FIG. 2 except that the jack has been raised so that the rearward end of the tractor has been raised from its supporting surface;

FIG. 4 is a side view of the device illustrating it being used to raise the front end of a tractor; and

FIG. 5 is a perspective view of an attachment for the device.

The jack of this invention is referred to generally by the reference numeral 10 while the numeral 12 refers to a tractor having a rear frame 14 positioned between the rear wheels 16 and 18. Tractor 12 also has a conventional horizontally disposed drawbar support 20 which supports the drawbar (not shown). Tractor 12 includes a pair of front wheels 22 (not shown) and 24 at the front end thereof which are supported by a conventional axle support assembly.

Jack 10 comprises a substantially horizontally disposed frame means 28 having ends 30 and 32 and an upper support area 34. A support means 36 is pivotally connected at its upper end to end 30 and has a transversely extending frame member 38 at its lower end. A pair of steel wheels 40 and 42 are rotatably mounted at the opposite ends of the frame member 38 as seen in FIG. 1. The wheels 40 and 42 have a narrow surface engaging area which enhances the maneuverability of the device since the narrow supporting surface tends to move over irregularities in the supporting surface more readily than if a broad supporting surface were provided.

A support means 44 is pivotally connected at its upper end to end 32 and has a transversely extending frame member 46 at its lower end. Steel wheels 48 and 50 are rotatably mounted at the opposite ends of the frame member 46 as illustrated in FIG. 1. The numeral

52 refers to a hydraulic cylinder means which is pivotally connected at its base end to the bracket 54 secured to frame member 38. The cylinder rod 56 of the hydraulic cylinder 52 is pivotally connected to the bracket 58 which is secured to frame member 46. The hydraulic cylinder 52 has a flexible conduit 60 secured thereto which is in communication with the interior of the cylinder to cause the retraction of the cylinder rod 56 into the cylinder 52. The conduit 60 is secured to the tractor hydraulic system in conventional fashion to provide a convenient means for operating the jack.

Ear 64 extends outwardly from frame member 38 and has an opening 66 formed therein. The numeral 68 refers to a positioning means including a handle 70, 15 wheels 72 and 74, and shaft stub 76 which may be inserted through the opening 66 to aid in positioning the jack beneath the tractor.

An elongated angle member 78 is secured to the rearward end of frame means 28 by bolts or the like and extends outwardly thereof as seen in FIG. 1. A bracket 80 is positioned on the rearward side of the angle member 78 for storing support blocks 82 and 84 therein at times. A pair of support blocks 86 and 88 are secured to the frame means 28 by chains 90 and may be positioned on the angle member 78 as illustrated in FIG. 1.

The numeral 92 generally refers to a support means which is removably and slidably mounted on frame means 28. Support means 92 comprises a center portion 94 which rests upon the support area 34 and a pair 30 of vertically disposed legs 96 and 98. The support blocks 82 and 84 may be positioned on the central portion 94 as desired for supporting a portion of the tractor frame means.

The numeral 100 also refers to a support means 35 which is removably positioned on the frame means 28. Support means 100 generally comprises a base 102 which may be secured to the frame means 28 by the J-shaped bolts 104 and 106. Length adjustable support posts 108 and 110 extend upwardly from the base 102 40 and have plates 112 and 114 at their upper ends respectively. The support means 100 may be used for supporting the front axle assembly of the tractor as illustrated in FIG. 4. Further, the support means 100 may be used to support any portion of the tractor as desired. The support means 100 may be used by itself or may be used in conjunction with the support means 92 or the frame member 78.

The normal method of operation is as follows. Assuming that the jack 10 is in its lowered position such 50 as illustrated in FIG. 1, the first step is to detachably secure the positioning means 68 to the ear 64 as previously described. The positioning means 68 is used to position the jack beneath that portion of the tractor that is to be raised. When the jack is in position, the flexible conduit 60 is connected to the tractor hydraulic system. If the tractor 12 has a horizontally disposed drawbar support 20, the support blocks 86 and 88 are positioned below the drawbar support 20. The support means 92 is then slidably moved on the frame means 28 55 so that it is beneath the desired portion of the tractor frame. The support blocks 82 and 84 may then be positioned on the center portion 94 if desired. The tractor hydraulic system is then actuated to cause the retraction of the rod 56 into the cylinder 52. Retraction of the rod 56 causes the support means 36 and support means 44 to be pivotally moved towards each other 60 which causes the frame means 28 to be raised with re-

spect to the supporting surface. The movement of the support means 36 and 44 towards each other is enhanced by the wheels rolling upon the supporting surface. As the frame means 28 is raised, the support blocks 86 and 88 engage the underside of the drawbar support 20 and the blocks 82 and 84 engage the underside of the tractor frame so that the rearward end of the tractor is raised to cause the rear wheels to be moved out of engagement with the supporting surface. The fact that the tractor is supported at two spaced apart locations permits the tractor to be split in conventional fashion to facilitate repair of the tractor differential, transmission, etc.

Some types of tractors do not have the drawbar support 20 and in those cases, the blocks 86 and 88 would be removed from the angle member 78. The angle member 78 would engage the rearward portion of the tractor and could be detachably secured to a portion of the tractor by the bolts 116 provided thereon.

The support means 100 provides a further means for supporting the tractor and may be used by itself or in conjunction with the other support means on the jack. For example, the support means 100 could be used in place of the support means 92 for supporting a portion of the rearward end of the tractor. Additionally, the support means 100 may be used to support the front axle assembly of the tractor if desired.

When it is desired to lower the tractor, it is simply necessary to operate the tractor hydraulic system control lever so that the rod 56 is permitted to extend from the cylinder. The extension of the rod 56 from the cylinder causes the support means 36 and 34 to be moved away from each other so that the frame means 28 is lowered until it moves out of engagement with the tractor. It should be noted that stops 118 are provided on the support means 36 and 44 which are adapted to engage the frame means 28 to limit the pivotal movement of the support means 36 and 44 towards each other.

Thus it can be seen that an extremely convenient and efficient jack has been provided which is ideally suited for use in conjunction with tractors or the like. The jack is extremely versatile in that it may be adapted for use with a variety of different tractor models and sizes. The jack is extremely stable in use and is easy to operate. Thus it can be seen that the jack accomplishes at least all of its stated objectives.

I claim:

1. A jack device comprising, a first substantially horizontally disposed frame means having first and second ends and an upper support area, a first support means having upper and lower ends and being pivotally secured at its upper end to said one end of said first frame means, a second support means having upper and lower ends and being pivotally secured at its upper end to said second end of said first frame means, said first support means having a pair of spaced apart wheels rotatably mounted on its lower end, said second support means having a pair of spaced apart wheels rotatably mounted on its lower end, an elongated angle member secured to said upper support area of said first frame means at said first end thereof and being disposed transversely with respect to said frame means, said elongated angle member adopted to removably support block members thereon at times, a third support means slidably and removably mounted on said upper support area of said first frame means adjacent said second end, said angle member and third support means supporting the object to be raised, a hydraulic cylinder means secured to and extending between said first and second support means and having a cylinder rod movable between extended and retracted positions, said first frame means being in a lowered position when said cylinder rod is in its extended position, the retraction of said cylinder rod into said cylinder means causing the lower ends of said first and second support means to be moved towards each other thereby causing said first frame means to be raised to permit the object supported thereby to be raised, and means for controlling the operation of said hydraulic cylinder means.

2. The jack device of claim 1 wherein a bracket 80 is secured to said angle member for storing support blocks therein at times.

3. The jack device of claim 1 wherein said third support means comprises an elongated transversely extending member slidably mounted on said upper support area, and upstanding legs at the opposite ends of said transversely extending member.
